DESIGN FOR A BROOCH OR SIMILAR ARTICLE

Larry Winters, Brooklyn, N. Y.

Application January 20, 1939, Serial No. 82,469

Term of patent 3½ years

To all whom it may concern:

Be it known that I, Larry Winters, a citizen of the United States of America, residing in New York city, in the Borough of Brooklyn, county of Kings, and State of New York, have invented a new, original, and ornamental Design for a Brooch or Similar Article, of which the following is a specification, reference being had to the accompanying drawing, forming part thereof, wherein,

I claim:

The ornamental design for a brooch or similar article, substantially as shown.

LARRY WINTERS.
